UNITED STATES PATENT OFFICE

NELSON M. BAKER, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS

OPHTHALMIC MOUNTING

Application filed October 3, 1929. Serial No. 397,053.

This invention relates to improvements in ophthalmic mountings and has particular reference to improved means and method for connecting the lens holding means of the said mounting.

A principal object of this invention is to provide means for securely attaching and at the same time easily removing the bridge in an ophthalmic mounting, and particularly in a goggle or eye protector where an adjustable or flexible type of bridging member is used.

Another object of the invention is to provide means of locking the removable bridge in place so that there will be no opportunity for it to slip or loosen while the mounting is in use.

Another object of the invention is to make possible the ready removal of soiled and worn bridge covering and its replacement by new ones without the use of special tools.

Another object of the invention is to provide simple means of adjusting the distance between the lens holding members in such a mounting.

Another object of the invention is to provide improved connecting means for the lenses of the flexible type bridge so that the lens holding means may be folded compactly for placing in the pocket or case.

Other objects and advantages of the invention will become apparent from the following description taken in connection with the accompanying drawings, and it will be apparent that many changes may be made in the details of construction, arrangements of parts and steps in the process without departing from the spirit of the invention as expressed in the accompanying claims. I, therefore, do not wish to be limited to the exact details shown and described as the preferred forms only have been shown by way of illustration.

In the drawings:

Fig. I is a front view of an ophthalmic mounting embodying the invention.

Fig. II is a perspective view showing the features of the invention and showing the parts separated.

Fig. III is a partial elevation of the mounting shown in Fig. I.

Fig. IV is a front view of the clip member shown in elevation in Fig. III.

In those types of eye protectors used in industrial occupation by welders, chippers and others, the eye cups do not usually have a rigid bridge member between them but on the contrary a very flexible member, such as a chain, which permits a close contact between the edge of the eye cup and the wearer's face. These chain bridges are often covered with a rubber tube or some similar protective member which prevents the chain from becoming rusted and discolored from perspiration and the like. As this chain is invariably permanently fixed to the eye cups at each end and not removable without a great deal of labor and damage, it will be readily seen that the protective covering will become soiled and unsanitary after a short time and that no means are provided for changing it. It is also a feature of these bridges that adjustment of the distance between the eye cups is usually made by twisting each eye cup and so shortening the chain, and while the desired distance could be obtained in this way by twisting the eye cup the adjustment was immediately lost when the mounting was removed from the face of the wearer. It will also be apparent that drawbacks are associated with twisting the eye cups for adjustment other than the non-permanency of adjustment, these drawbacks including an undue strain on the covering member from the unnatural position of the chain inside.

It is the prime object of my invention, therefore, to provide simple means to overcome these and other difficulties and to pro-

vide an efficient, economical and ingenious means to carry out the objects of the invention.

Referring to the drawings, in which similar reference characters designate similar parts throughout the several views, the lenses 1 are held in a lens rim or eye cup 2 in the usual manner. The eye cups are provided with a head band 3 for holding the mounting on the face of the wearer and are ventilated by the cut 4, preferably protected from the entrance of flying particles by the mesh screen 5. Extending between the eye cups 2 is a bridging member formed of a plurality of hollow ball members 6 which are made of thin sheet material and these hollow members are connected by a loose link 7 which is headed over on the inside thereof so as to produce a loose connection so that the series of connected balls has somewhat the action of a link chain. In order to provide a soft contact for the wearer's nose a tubular member 12 of tough rubber or other soft material may be slipped over the ball members comprising the bridging portion. Securing the bridge to each eye cup is an anchor member 8 bent to the shape shown in the drawing, and having its lower portion 9 formed as a curved plate and joined to the eye cups 2 by rivets 10 or other suitable securing means. The upper portion of the anchor plate 9 is bent to stand away from the eye cup when the plate is secured thereto and has a slot 11 which communicates with the hole 13 which is slightly smaller than the ball members 6, and has a chamfer or countersink 14 on its inner edge.

From Figs. I and III it will be seen that the anchor member 8 is spaced from the eye cups 2 enough to allow the cap 12 which holds the lenses 1 in place to be screwed down between the said anchor plates and the eye cups 2. The slot 11 is made large enough to allow the links 7 to slip freely therethrough but the hole 13 is too small to allow the ball members 6 to pass therethrough.

In the operation of the device the cap member 12 is first unscrewed from the cups 2 and the link member 7 passed through the slot 11 so that the end ball 6 of the bridging member will fit in the countersunk seat of the hole 13. The cap member 12 is then screwed down in place and pushes the ball member 6 onto the countersunk seat and so locks it in position. To remove the bridging member this proceeding is reversed and the cap member 12 is unscrewed, whereupon the ball member 6 may be pushed off its seat on the anchor plate 9 and the link member 7 drawn through the slot 11. The links of the chain of ball members 6 will set the distance apart of the eye cups for various wearers' pupillary distances. In order to shorten the distance one or more ball members may be clipped from the ball chain bridging member and a short-

ened bridging member inserted, as above described. This forms a ready means of adjustment and is quite permanent for any wearer as distinct from the prior art method of twisting one eye cup, which was obviously a very transitory adjustment and lost as soon as the mounting was removed from the wearer's head. The bridging member is easily removable by simply unscrewing the cap member 12, and this makes it a simple matter to change the rubber tubing when soiled or worn and so adds to the cleanliness of the goggle and prevents rusting of the metal chain, which would take place were a worn tubular covering to be used, as was inevitable in the prior art.

It will be understood that while I have shown the bridging member connected to both sides in a quickly removable manner, if desired the bridging member may be positively secured on one side allowing the whole adjustment for distance between the lenses to be made on the other side or the tubing to be removed by removing one side only.

From the foregoing it will be seen that I have provided simple and efficient means of carrying out the objects of the invention, particularly in providing simple means for detaching the bridging member of an ophthalmic mounting of the type described without danger of the bridging member becoming loosened while the mounting is in use.

Having described my invention, I claim:

1. In a device of the character described, a pair of lens holding members, a bridging member extending between the lens holding members, said bridging member having a plurality of separated enlarged portions connected by a relatively small neck portion, a bifurcated member on each lens holding member having its bifurcation spaced to admit the neck portion and having a seat adjacent the bifurcation to seat the enlarged portion, and cap members engaging the lens holding members and extending between the bifurcated member and lens holding means to retain the enlarged portion of the bridge in its seat.

2. In a device of the character described, a pair of lens holding members, a bridging member extending between the lens holding members, said bridging member having a plurality of ball members connected by relatively small link portions, a bifurcated member on each lens holding member having its bifurcation spaced to admit one of the link portions and having a seat adjacent the bifurcation to seat one of the ball members and cap members engaging the lens holding members and extending between the bifurcated member and lens holding means to retain the ball member of the bridge in its seat.

3. In a device of the character described, a pair of lens holding members, a lens in each of said lens holding members, a bridging

member extending between the lens holding members, said bridging member having a plurality of separated enlarged portions connected by a relatively small neck portion,
5 a bifurcated member on each lens holding member having its bifurcation spaced to admit the neck portion and having a seat adjacent the bifurcation to seat the enlarged portion and cap members engaging the lens holding members and extending between the bifurcated member and lens holding means to lock the enlarged portion of the bridge in its seat and the lens in the lens holding member simultaneously.
